CARL CURT HOENIG, OF BADEN, SWITZERLAND, ASSIGNOR, BY MESNE ASSIGNMENTS,
TO GENERAL ELECTRIC COMPANY, A CORPORATION OF NEW YORK.

SPEED REGULATION OF ELECTRICALLY-DRIVEN RING-SPINNING FRAMES.

1,178,447.

Specification of Letters Patent.

Patented Apr. 4, 1916.

Application filed January 11, 1909. Serial No. 471,794.

To all whom it may concern:

Be it known that I, CARL CURT HOENIG, a citizen of the Republic of Switzerland, residing at Parkstrasse 885, Baden, Switzerland, have invented certain new and useful Improvements in and Relating to the Speed Regulation of Electrically-Driven Ring-Spinning Frames; and I do hereby declare the following to be a full, clear, and exact 10 description of the invention, such as will enable others skilled in the art to which it appertains to make and use the same, reference being had to the accompanying drawings, and to letters or figures of reference marked thereon, which form a part 15 of this specification.

This invention relates to the speed regulation of spinning frames, particularly electrically driven ring spinning frames.

20 The yarn spun on ring spinning frames is generally wound on bobbins or tubes in conical layers with slightly crossed threads, enabling unwinding to take place without entanglement. To this end the yarn is 25 guided up and down along the rotating spindles by the ringrail which performs a reciprocating up and down motion. At the beginning of the spinning a conical base must be wound on the bare tube or bobbin, 30 unless the bobbin itself is formed with a conical base. On the top of this base a firm cop is then built up with normal conical layers. For this purpose the ringrail must be raised by the thickness of one layer after 35 each up and down motion and practically by the whole length of a bobbin or cop from "starting" until "doffing." This is accomplished by the coppering motion frame which is reciprocated by an actuating cam and is 40 provided with a ratchet wheel which is moved forward one step at each reciprocation of the frame in the ordinary manner to raise the ring rail by the thickness of one layer.

45 In accordance with my invention I provide a regulating gear for regulating the speed of the spinning frame which is so constructed and arranged that the speed is caused to rise and fall in accordance with 50 the reciprocation of the ring rail and also to progressively increase as successive layers are wound on the bobbin in such a

manner that the minimum speed of the frame, or as I prefer to call it, the speed of the base line, is progressively increasing 55 during a portion of the spinning operation or in a ring spinning frame as succeeding layers are wound on the conical base. This involves a novel mode of operation which constitutes an important feature of my invention. 60

In an electrically driven spinning frame the regulating gear is preferably arranged to control the speed of the motor which drives the whole machine and in order that 65 the speed may be varied to suit the winding process, I prefer to derive the speed regulation of the motor in some way or other from the mechanism which controls the motion of the ringrail. Thus the actions 70 of the machine and of the motor would be closely interconnected. The motion of the controlling members however may not be transferred immediately and separately to the regulating gear of the motor, because 75 the inertia of the mass of the motor and of the ring spinning frame have to be taken into account, and in consequence thereof in order to obtain the most correct regulation 80 of the motor the regulating gear must have first a reciprocating motion somewhat in advance of the motion of the ringrail at the reversing points, and secondly a progressive motion, to suit the fullness of the bobbins, 85 but not uniformly progressive as the motion of the ringrail.

The main object of this invention is to cause the speed of the spinning frame to vary in accordance with the rise and fall of the ring rail and to progressively increase 90 as successive layers are wound on the bobbin so that the speed of the base line corresponding to the lowest position of the ring rail in its reciprocating motion is progressively increased during a portion of the 95 spinning operation and more specifically to transform the motions introduced by the above-named members of a machine of the type referred to above and combine them 100 so that the resulting motion of the last member of the apparatus according to this invention communicates to the regulating gear the motion requisite for correct speed regulation of the motor.

The invention comprises a novel mode of operation and a novel apparatus whereby the speed of a spinning frame is caused to vary in the desired manner and more specifically consists in a regulating apparatus to work with electrically driven ring frames, so that two different motions are transformed and combined in a suitable manner, one of which motions is derived from a member of the spinning machine which produces the reciprocating motion of the ring-rail or from any other suitable member which causes or receives an equivalent motion, the other being derived from a member producing the progressive motion of the ring-rail or any member which causes or receives an equivalent motion in order to control by the resulting motion an apparatus which regulates the speed of the driving motor.

The invention also consists in a regulating apparatus of the kind referred to above which communicates the one of the two motions from the shaft of the cam of the coping motion or from any part rotating with same, and the other of the two motions from the axle of the ratchet wheel or any part rotating with same to the regulating gear.

The invention also consists in a regulating apparatus of the kind referred to above arranged so that one of the motions is transformed by this apparatus into a motion similar and related to the reciprocating motion of the ring-rail, but which takes into account the inertia of the masses of the motor and the machine in advance of the reciprocating motion of the machine between the reversing points.

The invention also consists in the improved regulating arrangements for electrically driven spinning frames hereinafter described.

Referring to the accompanying drawings—Figure 1 diagrammatically shows an arrangement according to one form of the invention, and Fig. 2 is a curve showing the relation between time and speed of the spindle, according to one form of the invention.

In carrying the invention into effect according to the form illustrated in Fig. 1, the motion of the ring-rail is governed by the lever *a* on the machine by means, for example, of a chain *b*. The cam *c* of the machine sets up a reciprocating motion in the lever, the chain, and the ring-rail. After each up and down motion the ratchet wheel *d*, which is fixed on the end of a shaft *e* carried by the lever *a*, is rotated one tooth, by means of pawl 10 intermittently, thereby causing the controlling chain *b*, to be wound on the shaft *e* of the ratchet wheel, and consequently a lifting of the ring-rail. Due to the actual motion of the ring-rail resulting from the above reciprocating and progres-

sive motion, the yarn is guided in the proper manner to the spindle for winding on the bobbin.

In order that the necessary motion be communicated to the regulator of the motor *C* (for example the brush shifter of a single phase motor) the following arrangement is made. The apparatus, Fig. 1, shows as an example how this may be performed. The apparatus consists principally of two cams *f* and *g*, which are suitably driven from elements of the machine, and two levers *h* and *i*, which communicate the transformed motion to the cord *k*, (rope, chain or band) laid over the small roller *m*, directly or indirectly operating the regulating gear of the motor. In this instance the cord is secured at *g* to a pulley *5* on the shaft *1* of the brush shifter of any known construction. The pulley *5* has secured to it a pulley *2*, to which is secured at *4* a cord or other suspension *3* carrying a weight *9*. The customary handle *7* rests against a stop *8*. The cam *c* causes the up and down swing of the coping lever *a* and is connected by means of chain, cord or band *n* with the cam *f*, which communicates a reciprocating motion to the lever *h* and therefore likewise to the cord *k*. The ratchet wheel *d* turned intermittently by the pawl 10 causes the chain *b* to be gradually wound on the shaft or drum *e*, and so effects the progressive motion of the ring-rail. The motion of cam *g* is derived from the same shaft and during one revolution communicates a motion to the lever *i* and the cord *k* suited to and in accordance with the fullness of the bobbin. The same end may of course be attained by other combinations of the different parts of the apparatus, likewise the reciprocating motion as well as the progressive motion may be derived by different means than those mentioned, either from the same members of the spinning machine or from members related to same.

There are several important advantages attending the use of an apparatus as described above, among which may be mentioned: The apparatus cannot fall out of step. Once set, it is impossible that the motor would be regulated in any other way than that to suit the different phases of the winding process. Any change in the position of the ring-rail by turning the ratchet wheel *d* is at once communicated to the regulating apparatus. As it is possible easily to change the shape of the cams and the length of the levers, there is no difficulty whatever in adapting the apparatus more particularly to the spinner's own liking and experience as regards the most suitable speed for the machine. The inertia of the mass of the motor and of the spinning frame may be taken care of by positioning the cam so

that the reciprocating motion of the regulating gear will take place somewhat in advance of the motion of the ring rail at the reversing points. If, for instance, the roller 5 *m* allows the cord *k* to hang loose, then the reciprocating motion of the lever is not communicated at all to the regulating gear and the motor runs at constant speed, being returned to normal position with the handle 10 7 against stop 8 by the weight 9. As the roller goes down the amplitude of the reciprocating motion communicated to *k* increases more and more until it reaches a maximum, as shown in the first part of the 15 curve, Fig. 2. Thereafter the amplitude of the reciprocating motion remains constant but the speed of the frame may be increased, as shown in the middle portion of the curve, Fig. 2, by the progressive motion of the cam 20 *g* lowering the initial position of the roller *m* and thus raising the speed of the base line and therefore the range of speed variation as succeeding layers are wound until the desired speed is reached. If required the speed 25 may be lowered again at the end of the spinning operation, as shown in the part of the curve beyond the break at the right in Fig. 2, to attain the most perfect regulation of the spinning machine.

30 I claim—

1. In an apparatus for controlling the speed of spinning frames and the like the combination with a speed regulating gear, the copping motion frame and its actuating 35 cam, of a lever, a cam to actuate said lever said cam receiving its motion from the cam of the frame, a second lever and a cam to operate it, said cam receiving its motion from the ratchet wheel of said frame, and means to combine the movements of the two 40 levers and to impart the resultant motion to the speed regulating gear.

2. In apparatus to control the motor of 45 electrically driven ring spinning frames, the combination with said motor and its controlling member, the copping motion frame and its actuating cam: of a lever, a cam to actuate said lever said cam receiving its motion from the cam of the frame, a second 50 lever and a cam to operate it, said cam receiving its motion from the ratchet wheel of said frame, and means to combine the movements of the two levers and to impart the resultant motion to the controlling member 55 of the motor to control the speed of the latter.

3. The method of operating spinning frames and the like which consists in varying the speed of the spinning frame back and forth over a predetermined range of speed 60 variation corresponding to the reciprocation of the ring rail and progressively raising the base line of said speed variation as successive layers are wound on the bobbin.

4. An apparatus for controlling the speed of spinning frames and the like comprising a driving means and means for controlling the same to increase and decrease the speed of the spinning frame as the ring rail reciprocates and for also progressively increasing the speed as successive layers are wound on the bobbin during the main portion of the spinning operation so that the minimum speed is increasing during the main portion of the spinning operation. 75

5. A drive for ring spinning machines and the like comprising means for increasing and decreasing the speed of the spinning machine in accordance with the reciprocating movement of the ring rail and means for progressively increasing the minimum speed as successive layers are wound on the bobbin during the main spinning operation. 80

6. A drive for ring spinning machines and the like comprising means for varying the speed of the machine over a predetermined range in accordance with the reciprocating movement of the ring rail during the main portion of the spinning operation 90 and means for progressively increasing the minimum speed of such range as successive layers are wound on the bobbin. 85

7. A drive for ring spinning machines and the like comprising an electric motor, a speed controller therefor, and conjoint means for moving the same to vary the speed of the spinning machine in accordance with the reciprocating movement of the ring rail and progressively increase the minimum speed as successive layers are wound on the bobbin during the main portion of the spinning operation. 95 100

8. A drive for ring spinning machines and the like comprising means for varying the speed of the spinning frame back and forth over an amplitude which gradually increases up to a predetermined value and continuing such variation with fixed amplitude during the spinning operation, and means for gradually increasing the minimum speed of such fixed amplitude as successive layers are wound on the bobbin. 105 110

9. A drive for ring spinning machines and the like comprising means for varying the speed of the spinning frame back and forth in accordance with the movement of the ring rail but in advance thereof at the reversing points, and means for progressively increasing the minimum speed as successive layers are wound on the bobbin. 115 120

10. A drive for ring spinning machines and the like comprising means for varying the speed of the spinning frame back and forth in accordance with the movement of the ring rail but in advance thereof at the reversing points over an amplitude which gradually increases up to a predetermined 125

value and continuing such variation at fixed amplitude during the spinning operation, and means for gradually increasing the minimum speed of such fixed amplitude as successive layers are wound on the bobbin.

In testimony that I claim the foregoing

as my invention, I have signed my name in presence of two subscribing witnesses.
